US0D1060310S

(12) **United States Design Patent** (10) Patent No.: **US D1,060,310 S**
(45) Date of Patent: ** Feb. 4, 2025

(54) **REMOTE CONTROL APPARATUS
WIRELESS**

(71) Applicant: **SOMFY ACTIVITES SA**, Cluses (FR)

(72) Inventors: **Mathieu Prevoteau**, Meythet (FR);
Thomas Desagre, Sallanches (FR)

(73) Assignee: **SOMFY ACTIVITES SA**, Cluses (FR)

(**) Term: **15 Years**

(21) Appl. No.: **35/517,650**

(22) Filed: **Jun. 8, 2023**

(80) **Hague Agreement Data**

Int. Filing Date: **Jun. 8, 2023**

Int. Reg. No.: **DM/229740**

Int. Reg. Date: **Jun. 8, 2023**

Int. Reg. Pub. Date: **Jun. 30, 2023**

(30) **Foreign Application Priority Data**

Dec. 21, 2022 (WO) WIPO126701

(51) **LOC (15) Cl.** **14-03**

(57)

CLAIM

The ornamental design for a remote control apparatus wireless, as shown and described.

DESCRIPTION

The patent or application file contains at least one drawing executed in color. Copies of this patent or patent application publication with color drawing(s) will be provided by the Office upon request and payment of the necessary fee.

1.1 : Front perspective

1.2 : Front

1.3 : Back

1.4 : Right

1.5 : Left

1.6 : Top

1.7 : Bottom

The broken lines showing portions of the article form no part of the claimed design. The color yellow showing portions of the article, which extends to a respective boundary but does not include the boundary, form no part of the claimed design.

1 Claim, 7 Drawing Sheets
(1 of 7 Drawing Sheet(s) Filed in Color)
